CLAIM

The ornamental design for a display screen or portion thereof with icon, as shown and described.

DESCRIPTION

FIG. 1 is a front view of a display screen or portion thereof with icon showing our new design according to a first embodiment; and,

FIG. 2 is a front view of a display screen or portion thereof with icon showing our new design according to a second embodiment.

The broken line showing of a display screen or portion thereof with icon is included for the purpose of illustrating portions of the article that forms no part of the claimed design.

1 Claim, 1 Drawing Sheet
